Attorney

UNITED STATES PATENT OFFICE.

EDMOND FOUCHE, OF PARIS, FRANCE.

BLOWPIPE.

1,418,245.

Specification of Letters Patent. Patented May 30, 1922.

Application filed December 27, 1919. Serial No. 347,668.

To all whom it may concern:

Be it known that I, EDMOND FOUCHE, a citizen of the French Republic, and resident of 98 Avenue Niel, Paris, France, have 5 invented certain new and useful Improvements in Blowpipes, of which the following is a specification.

The oxy-acetylene blow pipes at present used for autogenous welding, generally 10 comprise an inner oxygen jet around which the acetylene is admitted, the oxygen forcing the acetylene through a mixing conduit in the body of the apparatus before leaving the outlet nozzle.

Practice has shown that this arrangement has the drawback that on leaving the nozzle, the mixture is richer in oxygen in the centre than at the periphery, owing to which a flame cannot be obtained which is neutral 15 throughout. The short period of contact between the two gases in the mixing conduit of the apparatus is insufficient for completely mixing the two gases.

The invention has for its object to remedy 20 the above stated drawback and consists in providing means for giving the oxygen jet an extremely thin annular formation and means for admitting the acetylene both inside and outside of the annulus so as to produce 25 an intimate commingling of the two gases in the conduit before leaving the outlet nozzle.

Owing to the thinness of the annular jet of oxygen, and to the contact of acetylene 30 on both sides thereof, the diffusion of the two gases is almost instantaneous, and the mixture escaping from the nozzle is practically homogeneous throughout. In these conditions, the flame obtained is incapable 35 of either carburetting or oxidizing locally, and the consumption of oxygen is in accordance with theoretical indications according to which, with pure acetylene and oxygen, the volumes of the two gases simultaneously 40 used, should be practically equal.

It is obvious that the invention can be carried out in various ways, and that the apparatus enabling a thorough mixture of the two gases to be obtained by the process indicated, can be of very different constructions.

A blow pipe according to the present invention is shown in longitudinal cross-section in the accompanying drawing by way 55 of example.

Referring to the accompanying drawing

it will be seen that the blow pipe comprises a body 1 having an outlet nozzle 2 and provided at the rear with a breech portion 3 and a handle 4.

The breech portion 3 has a cylindrical recess or bore in which are arranged injectors constituted by two concentric tubes 5, 6, the forward ends of which are of frusto-conical form and are of such outline as to leave between them only a very narrow annular opening. These tubes are held in spaced relation by means of rings 8 secured to the tube 5 and provided with longitudinal grooves to enable the gas to circulate freely 60 between the concentric tubes. The tube 5 is provided at the lower part with inlet orifices 9 and has a solid end 10 screw threaded and provided with an operating button 11. In the bore of the breech portion 3, level 65 with the orifices 9, is arranged a recessed and perforated ring 12, between stuffing box packings 13, 14, which ring forms an admission chamber through which the gases pass before issuing through the orifices 9 into 70 the tube 5. The packings 13, 14 are compressed by a nut 18 between two washers 15 and 16, the former of which rests against the open rear end of the tube 6, which latter rests in turn, with its forward conical end, 75 against a correspondingly shaped shoulder 17 in the front end of the breech portion.

It will be seen that in this way the nut 18 is used not only to compress the packing 13, 14 to ensure a tight joint of the ring 12, but 80 also to force and hold the conical end of the tube 6 against the shoulder 17, thus ensuring a tight joint at this point.

The gases are supplied to the injectors by 85 the following means:

The handle 4 is provided at its end with nipples 19 and 20 to which are secured flexible gas supply pipes so as to connect them respectively to the pipes 21, 22; the former of these pipes terminates 90 in a conduit 23 which opens into the bore in the breech portion 3 opposite an orifice 24 provided in the tube 6. The pipe 22 terminates in a conduit 25 opening 100 into conduits 26, 27 which latter terminate 105 respectively, one in a conduit 28 in the mixing chamber 29, and the other in a chamber formed by the perforated ring 12.

Oxygen is admitted into the breech portion 110 through the pipe 21 and passes through the conduit 23, through the orifice 24 into the annular space between the two tubes 5

and 6 and escapes through the annular nozzle 7 in the form of a thin annulus the thickness of which can be regulated by adjusting, by means of the knob 11, the tube 5 which has the function of a needle valve.

The acetylene is admitted into the breech portion 3 through the pipe 22, enters the conduit 25 and divides into two currents which pass, one into the mixing chamber 29 through the conduit 26, and the other, through the conduit 27, into the admission chamber formed by the recessed ring, the latter current entering the tube 5 through the orifices 9 and escaping through the end of 15 the said tube.

It will be seen that in this way the oxygen is discharged through the annular orifice 7 in the form of an annulus the thickness of which can be regulated at will and can be 20 reduced to almost nil whilst the acetylene is admitted both internally and externally of the annulus, without the three streams of gas thus formed being permitted to mix before reaching the mixing chamber 29. 25 The gases then pass through the central conduit 30 of the body 1 of the blow pipe and reach the outlet nozzle 2.

Although the foregoing description refers to a blow pipe for oxy-acetylene gas, it will 30 be readily understood that it may be used for any other gases, for instance the oxygen could be replaced by atmospheric air or any other gases capable of supporting combustion, and in place of the acetylene, hydrogen, 35 lighting gas, combustible vapours or liquids may be used.

Moreover, the arrangement of the gas currents may be changed if desired, that is to say the annulus may be formed by the fuel, 40 gas or liquid, in which case of course the oxidizing agent would be injected internally and externally of the annular jet.

Finally, in order to obtain an absolutely perfect mixture, either several similar annular jets may be formed by using a larger 45 number of concentric tubes, or the annular jet could be combined with a full central jet by using three concentric tubes instead of two.

50 The arrangements hereinbefore described are given merely by way of example. The shapes, dimensions and details of construction may be varied without departing from the spirit of the invention.

55 Having now particularly described and ascertained the nature of my said invention and in what manner the same is to be performed, I declare that what I claim is:—

1. In a gas blowpipe, the combination with 60 a central pipe through which one of the gases passes, of a pipe concentric with the former through which the other gas passes, having a constricted portion of conical form at the upper part of the concentric pipe to 65 deliver the gas in the form of an annular

jet and to form an ejector, a chamber in the form of an enlarged pipe forming a mixing chamber for the gases, a nozzle terminating said chamber, a screw regulating device for moving said central pipe axially, and means 70 for bringing to the base of the mixing chamber a jet of gas perpendicular to the annular jet.

2. In a gas blowpipe, a central pipe through which one of the gases passes, a 75 screw regulating device for moving said tube axially, a pipe concentric with said central pipe through which the other gas passes, a constricted conical portion at the upper part of said concentric pipe to deliver the gas in 80 the form of an annular jet and to form an ejector, a chamber in the form of an enlarged pipe for the reception of the annular jets of gas and forming a mixing chamber, a nozzle terminating said chamber, a passage 85 emptying at the base of the mixing chamber perpendicularly to the concentric jets of gas, and means to simultaneously bring the gas into said passage and into the central pipe of the ejector. 90

3. In a gas blowpipe, a central pipe through which one of the gases passes, a screw regulating device for axially moving said pipe, a pipe concentric with said central pipe for the passage of the other gas, a conical constricted portion at the upper part of 95 said concentric pipe to deliver the gas in the form of an annular jet and to form an ejector, a chamber in the form of an enlarged pipe receiving the annular jets of gas 100 and forming a mixing chamber, a nozzle terminating said chamber, a first passage emptying at the base of said chamber perpendicularly to the concentric jets of gas, a second passage parallel with the pipes and 105 communicating with the gas passage to the blowpipe, a third passage parallel with the first passage and communicating with the second passage, and means placing the third passage in communication with the central 110 pipe of said ejector.

4. In a gas blowpipe, a central pipe through which one of the gases passes, a screw regulating device for moving said pipe axially, a pipe concentric with said central 115 pipe for the passage of the other gas, a conical constricted portion at the upper part of said concentric pipe to deliver the gas in the form of an annular jet and to form an ejector, a chamber in the form of an enlarged 120 pipe receiving the annular jets and forming a mixing chamber, a nozzle terminating said chamber, a passage emptying at the base of the mixing chamber and arranged perpendicularly to the axis thereof, a passage perpendicular to the former and connected to the gas intake, another passage perpendicular to this latter and passing to the wall of the chamber containing the ejector, a sleeve 125 in the form of a cupola arranged in the last 130

mentioned chamber and supporting the central pipe, the central pipe being provided with openings for the introduction of gas, packings between the sleeve and the corresponding ends of the exterior pipe of the ejector, and a stuffing box surrounding the screw regulating device of the central pipe.

5. A gas blow pipe including a tube for furnishing an oxidizing medium and provided at one end with a restricted portion, means for furnishing an oxidizing medium to the interior of said tube, a second tube arranged within the other tube and spaced from the same to provide an annular passageway, one end of the second tube terminating adjacent to the restricted portion of the first mentioned tube, means for furnishing fuel to the interior of the second tube, a third tube surrounding the other tubes and provided with a bore, and means for introducing a second supply of fuel into said bore at the point of meeting of the restricted portion of the first tube and the end of the second tube.

25 6. A blow pipe including an outer tube

provided at one end with a nozzle and having a bore provided with a restricted portion intermediate its ends, the portion of said bore on one side of the restricted portion forming a mixing chamber, a second tube mounted in the bore and having a nozzle extending into said mixing chamber, means for furnishing an oxidizing medium to the interior of the second tube, a third tube arranged within the second tube and spaced therefrom to provide an annular passageway to receive the oxidizing medium, the third tube having one of its ends arranged at the point of the nozzle of the second tube, and means for introducing fuel into the third tube and to said mixing chamber at a point adjacent to the nozzle of the second tube.

In testimony whereof I have signed my name to this specification in the presence of two subscribing witnesses.
